(57) **CLAIM**

The ornamental design for a cuff for remote ischemic conditioning, as shown and described.

DESCRIPTION

FIG. 1 is a top perspective view of the cuff for remote ischemic conditioning;

FIG. 2 is a top, plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken lines in the drawing views illustrate unclaimed portions of the cuff for remote ischemic conditioning and form no part of the claimed design.

1 Claim, 5 Drawing Sheets
